UNITED STATES PATENT OFFICE.

FRANK L. BAMFORD, OF DETROIT, MICHIGAN, ASSIGNOR TO C. M. HALL LAMP COMPANY, OF DETROIT, MICHIGAN, A CORPORATION OF MICHIGAN.

LAMP CATCH.

Application filed September 30, 1925. Serial No. 59,659.

The invention relates to vehicle lamps and has more particular reference to the means for holding the lens ring in closed position and the invention consists in the novel construction of such retaining means as herein-after set forth.

In the drawings:

Figure 1 is a longitudinal section through a portion of a lamp housing and ring showing my improved catch applied thereto.

Figure 2 is a perspective view of one of the loops.

Figure 3 is a bottom plan view of a portion of Figure 1.

A is a lamp housing of any suitable construction which is provided with a reinforcement B to which the securing shank C is attached. D is a lens holding ring containing the lens D' having suitable engagement with the forward edge of the housing A, such as the shoulder bearing E, forwardly extending flange F and inwardly extending flange G on the housing, with which parts the ring is telescopically engaged. H is a sealing gasket which is arranged between the flange G' formed on the reflector G'' and the lens D' forming a yielding bearing for the latter, the flange G' having a bearing on the flange G formed on the housing.

The lens ring is preferably provided with a yieldable hinge engagement with the housing which, as shown, comprises a loop spring member I having at one end a hook I' for engaging an aperture in the flange G. The opposite end I² of this spring passes through a slotted aperture J in the member F and engages a slotted bearing K in the ring member, while the intermediate portion of the spring has a bearing on a portion of the housing whereby outward movement of the loop is prevented. Thus, when the ring is angularly inclined, the slotted bearing K may be engaged with the projecting end I² of the spring which latter will yield as the lens D' engages the sealing ring H.

To retain the opposite side of the lens ring I have provided a loop spring L having one end anchored to the housing and its opposite end extending outward through a slot therein and pivotally connected to a hook member M. This hook member is engageable with an aperture in the ring D and because of the resiliency of the loop, is yieldably adjustable. Thus the ring D is free to seat itself against the gasket H and

the loops I and L will yield to permit such seating and to maintain a suitable tension for holding the ring to its seat.

The construction just described is exceedingly simple and inexpensive to manufacture and in use effectively secures the lens ring while permitting easy detachment of said ring whenever necessary.

What I claim as my invention is:

1. In a lamp, the combination with a casing having a slot and a lens ring engageable with the casing, of means for yieldably retaining said lens ring in position on the casing, said means including a loop spring having one end detachably anchored to the casing and its other end extending through the slot in the casing for engagement with the said lens ring, said loop spring being provided with means for bracing the end extending through the slot against movement in any direction except a direction parallel to the axis of the said lamp.

2. In a lamp, the combination with a slotted casing having a flange at its forward end and a lens ring engageable with said casing, of means for yieldably retaining said lens ring in position comprising a loop spring having a portion detachably anchored to the said flange, a second portion extending through the slot in the said casing for engagement with the lens ring and a third portion bearing against the said casing for bracing the portion extending through the slot against movement in any direction except a direction parallel to the axis of the said lamp.

3. In a lamp, the combination with a casing having a flange and a slot at its forward end and a lens ring engageable with said casing, of means for yieldably retaining said lens ring in position comprising a loop spring having one end detachably anchored to the said flange, its other end extending through the slot in the said casing for engagement with the lens ring and its intermediate portion offset for abutting engagement with the said casing to brace the end extending through the said slot against movement in any direction except a direction parallel to the axis of the said lamp.

4. In a vehicle lamp, the combination with an apertured housing and a lens holding ring engageable therewith, of yieldable retaining means for said ring comprising a

pair of loop springs each having one end detachably anchored to said housing and the opposite end projecting outward through an aperture therein, means on said ring for engaging the end of one of said springs to form a yieldable hinge connection and a hook catch pivotally secured to the end of the other of said springs for hooked engagement with the opposite side of said ring.

10 5. In a lamp, the combination with a lens holding ring having a slot, of a housing having a forwardly projecting portion for telescopically engaging said ring and provided with an inwardly extending flange and upper and lower slots, a sealing gasket between said inwardly extending flange and the lens, and means for yieldably retaining said

ring comprising a loop spring having one end detachably anchored to the inwardly extending flange of said housing and its opposite end projecting outward through the upper slot therein to engage the slot in said ring, a second loop spring on the diametrically opposite side of said casing having one end detachably anchored thereto and the 20 opposite end extending outwardly through the lower slot therein, and a hook member pivotally connected to the outer end of said last mentioned spring member for hooked engagement with the opposite side of said 25 ring.

In testimony whereof I affix my signature.

FRANK L. BAMFORD.
